CLAIM

I claim the ornamental design for a car top carrier, as shown and described.

DESCRIPTION

FIG. 1 is a perspective view of a car top carrier constructed in accordance with the present invention;

FIG. 2 is a front view thereof;

FIG. 3 is a rear view thereof;

FIG. 4 is a top view thereof; and,

FIG. 5 is a side view thereof, the opposite side being identical thereto.

The broken line(s) shown in the drawings are for illustrative purposes only and form no part of the claimed design.

The bottom of the design is flat and unornamented, so the bottom view has been omitted.

The left side of the design is identical to the right side, so the left view has been omitted.

The stippling and shading lines shown in the drawing(s) represent the approximate three-dimensional contour of the design, and are not intended to indicate surface decoration.

Portions of the car top carrier that are not shown in the drawing(s) form no part of the claimed design.
